JOHN L. CREVELING, OF AUBURN, NEW YORK.

ELECTRIC REGULATION.

1,394,972.

Specification of Letters Patent. Patented Oct. 25, 1921.

Application filed October 24, 1914. Serial No. 868,404.

To all whom it may concern:

Be it known that I, JOHN L. CREVELING, a citizen of the United States, residing at Auburn, in the county of Cayuga and State 5 of New York, have invented new and useful Improvements in Electrical Regulation, set forth in the annexed specification and drawing forming a part thereof.

My invention pertains to that class of electric regulation wherein it is desired to regulate the voltage across a circuit, or the current flowing in a circuit.

My invention has for its particular object to provide means whereby such regulation 5 may be carried out automatically and within predetermined narrow limits of variation.

In the drawing, Figure I. is a side elevation and partial section of one type of apparatus embodying my invention.

20 Fig. II. is a bottom plan of the apparatus shown in Fig. I.

Fig. III. is a partial elevation of a modified form of apparatus comprehending my invention, and shows, in elevation, parts 25 which may be substituted bodily for those parts appearing below the section indicated at A—B in Fig. I.

Fig. IV. is a bottom plan of that modification shown in Fig. III.

30 Fig. V. is a diagrammatic representation of the devices indicated in the above figures, and indicates one method of connecting up the same for use in service.

Fig. VI. shows a modified form of one 35 portion of the apparatus shown in Figs. I. and II., and shows the said portion in end elevation and partial section.

Fig. VII. is a side elevation of that modification shown in Fig. VI.

40 Fig. VIII. is a partial section and bottom plan of a modification of some of the parts indicated in Figs. III. and IV.

Fig. IX. is a diagrammatic representation 45 of the preferred magnetic field flux in that apparatus shown in Figs. I. and II.

Fig. X. is a diagrammatic representation of the preferred magnetic field flux when using that modification of the apparatus of Figs. I. and II. shown in Figs. VI. and VII.

50 Fig. XI. is a diagrammatic representation of the preferred form of field flux employed when using that modification indicated in Figs. III., IV. and VIII.

In the drawing, and referring particularly to Figs. I. and II., 1 represents a frame

or casting for supporting and holding in proper operative relation the various parts of one form of embodiment of my invention, and is provided with the insulated rods 2, serving as upper and lower retaining members 60 for the various disks or contacting members 4, the regulating effect of which may be varied by variations in pressure thereupon. The members 4 in this instance may be considered as indicating a typical 65 carbon pile restrained from lateral movement as by means of the insulating rods 3, which are shown carried by the frame 1, in Fig. II., but with the ends broken away in Fig. I. for sake of clearness. 70

The said carbon pile 4 may be electrically connected into the circuit to be regulated as by means of terminals or pig-tails 5. One end of the pile 4 is pressed against the flange or disk 6, and electrically insulated therefrom, as indicated. The said flange 6 is preferably carried by a stem 7, fitting freely within the bushing 8 and peripherally threaded member 9, tending, when made up into the thread of the sleeve 11, to compress 80 the spring 10 and force the bushing 8 into that position shown in the figure where its flanged portion is shown as resting against the inturned flange of the sleeve 11, which sleeve has its exterior threaded into the 85 frame 1, as shown.

The other end of the pile 4 is pressed by the member or flange 12, insulated therefrom, as indicated, and pivotally carried upon one extremity of the lever 13, as indicated by dotted lines at 14, the said lever being pivoted to the frame 1, as indicated at 15, with its upward extremity free to move within the open portion of the frame 1, indicated by the dotted line 16 in Fig. I., and 95 shown more clearly in the plan in Fig. II.

The said lever 13 is pivoted at its lower extremity 17 to the compression link or member 18, passing through an opening indicated in dotted lines within the depending 100 member 19 of the frame 1, which depending member is preferably made of magnetic material, and, if desired, the entire frame 1 may be made of cast-iron.

The member 18 is pivotally connected, as 105 indicated at 20, to a yoke provided with limbs 21, preferably of non-magnetic material, carrying the shoes or members 22, preferably made of magnetic material of high permeability. 110

The yoke having the branches 21 is provided with the extension 23, pivotally supported within an opening in the depending portion of the frame 24, as indicated at 25, 5 in such manner as to freely swing within certain limits therein. And, an extension of the member 23 is provided with a counterweight 26, and is normally drawn upwardly by spring 27, adjustable as by nut 28.

10 29 represents any suitable type of dashpot, which may be connected in any suitable manner with the member 23, as shown, for example, connected by the links 30 on opposite sides of the counterweight 26, engaging a pin through said weight.

15 31 is a stop, serving to limit the swinging movement of the member 23 in one direction.

20 The depending members 19 and 24 have attached thereto, as indicated, magnet cores 32 provided with pole pieces 33, defining the circular openings or air gaps 34. And the 25 said magnet cores are provided with suitable windings, indicated at 35, and for sake of example, shown connected together in series, in Figs. I. and II.

25 In practice, I choose to make the members 18, 21 and 23 of a light non-magnetic material, as for example, an alloy of aluminum, so that the said moving parts will have as little inertia as possible, and the 30 said parts may be balanced by counterweight 26 and the plunger of the dashpot 29. And, in order to decrease the friction at the various 35 pivotal points, any of the well known types of ball bearings or other anti-friction journals may be used.

30 In the apparatus shown in Figs. I. and II. it will be noted that the magnetic shoes or 40 armatures 22 are separated from each other by portions of the non-magnetic limbs 21. And with this construction, I so wind the coils 35 as to set up a magnetic circuit, as indicated in Fig. IX., or in the reverse direction to that shown by the arrows in said figure, it merely being preferable that the 45 magnets have their cores in what might be termed series, to form a single magnetic circuit, the particular direction being of no 50 moment.

50 If desired, the shoes or armatures 22 may be connected together mechanically and magnetically as by the core 36, shown in Fig. VI., and the said core may be provided with a winding 37, shown in Fig. VI. in section, and in elevation in Fig. VII. This winding may be either in series or shunt with the field coil windings 35, as desired.

60 When this modification is used, it is preferable that the coils be so wound as to set up two magnetic circuits, each passing through the core 36, as indicated in Fig. X., it of course being obvious that the direction 65 of the said flux may be as indicated by the

arrows in Fig. X., or the exact reverse thereof, so long as the mutual relation of the two fluxes remains the same.

In that modification shown in Figs. III. and IV., the dashpot 29 and other members 70 extending to the right of the depending portion of the frame 1, are suppressed, and the lever 13 is pivotally connected with the member 38, which is pivotally connected, as at 39, with a similar member 40, pivotally connected at 25.

75 The magnet cores 32 are provided with pole pieces 41, the juxtaposed faces of which conform to the outer surface of the cylinder of non-magnetic material 42, supported thereby 80 and forming the cylinder of a dashpot, provided with the plunger 43, carrying the stem 44, so arranged that as the plunger 43 is raised the stem 44, by raising the pivotal point 39 between levers 38 and 85 40, will cause the lever 13 to be swung about its pivot 15. Springs 45 engage the extremities of the pin or pivot 39 and tend to draw the same downwardly, and may be adjusted by the screw 47, threaded in the yoke 90 46 attached to the two springs, as shown.

If a wet dashpot be used,—as for example, one containing glycerin or oil, the plunger 43 may be made of iron or other magnetic material, and may be solid or hollow, as 95 desired, and may practically fill the cylinder 42, or the iron portion may be surrounded by a non-magnetic portion, as indicated in section at 48 in Fig. VIII., if desired to increase the gap around the said plunger. 100

Or, if a dry dashpot be chosen, that portion indicated at 48 in Fig. VIII. may readily be made of graphite, which will serve both as a spacing member and a lubricant.

Further, if desired, the dashpot core or 105 plunger may contain a winding 49, as indicated in section in Fig. VIII., and the said winding may be either in series or multiple, with the field exciting windings 35. In using either form of the apparatus shown in 110 Figs. III., IV. and VIII. it is preferable that the windings work together to set up the magnetic fluxes indicated in Fig. XI. or an exact reverse thereof wherein the mutual relations remain the same. 115

In Fig. V., 50 represents a dynamo or generator, the positive lead of which is represented at 51, and connected with the positive terminals of the storage battery 52 and lamps or other translating devices 53, the 120 negative terminals of the said translating devices being connected with the lead 54, carried to one of the connections 5 of the regulating element 4, the opposite connection of which may be carried to the negative pole of the storage battery 52 and back to the generator through a suitable type of switch, as indicated at 55.

125 In this diagram the coil 56 in multiple across the translation circuit is indicated as 130

tending to draw its plunger 43 in a downward direction against the action of the spring 57 in such manner as to swing the arms 38 and 40 downwardly and lessen the pressure upon the pile 4, which is the equivalent of the oppositely acting tendency of the structure of Figs. III. and IV., in which the arms 38 and 40 are conversely arranged.

10 An operation of my invention is substantially as follows:

Referring particularly to Figs. I. and II., the carbon pile 4 may be connected as by means of the leads 5 with the circuit intended to be regulated, and the windings 35 may be of low resistance and in series with a circuit in which fluctuations in current are desired to operate the regulator; or the said windings may be of high resistance and in 20 shunt to a circuit, the voltage across which is to be the standard of regulation. In either event, the coils 35 are so wound that with a normal operation of the system, whatever its form may be, the said coils maintain a 25 powerful field across the gaps 34.

Therefore, the members 22 are attracted powerfully in an endeavor to shorten the effective length of the said gaps, and any motion given to the shoes 22 by the influence 30 of the said windings will cause the same to swing upwardly about the pivot 25, against the action of the spring 27, tending to normally hold the shoes in the position shown in the drawing, wherein the lever 23 is held 35 against the stop 31; too sudden movement being arrested by the dashpot, as indicated at 29. Upward movement of the shoes 22, together with members 21 and 23, will cause the member 18 to swing the lever 13 about 40 its pivotal point 15 in a counter-clockwise direction, and thus move the member 12 in such manner as to decrease the pressure upon the carbon pile 4, and increase the resistance thereof.

45 And, I usually prefer to so adjust the carbon pile 4, that when the movable parts of the apparatus are in the positions indicated in Fig. I. the carbon pile will be subjected to considerable pressure, and its resistance reduced to the minimum.

And, for the purpose of this adjustment, I may employ, if desired, the spring adjusting member or device shown in connection with the shell indicated at 11, with which 55 arrangement the nut 9 may be screwed into the shell 11 until the spring 10 is so compressed as to determine the maximum pressure desired upon the pile 4. Then the shell 11 may be screwed into the frame 1 until 60 the desired pressure is brought upon the pile 4.

Then, with this arrangement, if the pile expand, as for example, under the influence of heat, the same may cause a slight yielding 65 of the spring 10, without any injurious in-

crease in compression upon the pile. However, this spring yielding means may be suppressed, if desired, and a solid member or bushing be used in place of the shell 11, properly perforated to carry the stem 9.

70

It will be noted that the type of magnetic circuit shown in Fig. I. is such as to cause a great effort to swing the members 22 in a circular direction, and provide an attracting magnet of long and powerful range.

75

Further, when the shoes 22 are drawn within the gaps 34 they will be acted upon substantially equally in both lateral directions, relieving heavy thrust, due to the attraction of either of the magnets upon the 80 pivot 25, and thus reduce friction at said point.

Also, it will be noted, that I may so proportion the arms of the lever 13 as to exert great pressure upon the pile 4, with lesser 85 pressure being exerted against the pivotal connection 17. And that, inasmuch as the members 18 and 23 pivotally connected together as at 20, form a toggle-joint, a great addition in pressure may be exerted upon 90 the pile 4 when the shoes 22 are approaching the position shown in the drawing, for the well known principle of the toggle-joint is herein utilized, as in printing presses and the like, to increase the pressure per unit 95 of movement of the shoes 22, as the pressure upon the pile 4 increases.

It will be obvious, that in employing my invention as above set forth with regard to Figs. I. and II. it will be preferable to cause 100 the magnet windings 35 to be so grouped as to cause the magnetic flux through the same and the shoes 22 to take place in a direction as set forth above in describing Fig. IX.

The shoes 22 may be united by the magnetic member 36 carrying the coil 37, as shown in Fig. 6. And, the operation will be substantially the same as outlined above with regard to Figs. I. and II., save that the magnetic pull upon the shoes 22 may be 110 greater, if desired, owing to the winding 37, which may be either in series or multiple with the windings 35, as desired.

This construction may be made more sensitive, inasmuch as smaller variations in current throughout the actuating windings will cause greater variations in the mechanical effort of the fields of said windings.

With this arrangement, it is preferable that the various actuating windings be so 120 connected as to set up two magnetic circuits, as indicated in Fig. X. and above described with reference thereto.

In that modification of my invention shown in Figs. III. and IV., the dashpot 29, 125 counterweight 26, and other members appearing on the righthand side of the depending portion of the frame 1, are suppressed, and the carbon pile 4 may be operated through the instrumentality of the lever 13, 130

as above described with regard to Figs. I. and II.

However, in this construction the lever 13 is operated by the levers or links 38 and 40, forming in effect a toggle-joint, the members of which are pivotally united at 39 which may be termed the knuckle, and which, in a preferred form of my invention, is not allowed by the stem 44 (or links if preferred) to descend sufficiently to cause the levers 38 and 40 to form between themselves an angle of 180°.

Therefore, with this construction it is usually preferable to omit the spring 10 within the sleeve 11 and make the adjusting bushing or sleeve non-compressible, for the expansion of the pile 4, if necessary, may be relieved if it exert sufficient force to cause the knuckle 39 to be elevated against the action of springs 45. When the current in the coils 35 is sufficient that their magnetic effect upon the plunger 43 is sufficient to overcome the springs 45, the plunger 43 will be lifted, and the knuckle 39 pressed upwardly in such manner as to decrease the pressure upon the pile 4 and increase the resistance in the circuit to be regulated. And, if the current in the said coils 35 then fall, the reverse operation will take place. If desirable to increase the power of the magnetically operating members in this form of construction shown in Figs. III. and IV., this may be done by providing a winding within the dashpot plunger, as shown in Fig. VIII., wherein the magnetic portion of the plunger is shown shuttle-shaped, and provided with a winding 49 causing the magnetic portion and said winding to assume a substantially circular section, and this so wound core is fitted into a sleeve 48, of non-magnetic material, giving a truly cylindrical form to the movable member or dashpot plunger, which will operate in substantially the same manner as did the plunger 43 in the above description of Figs. III. and IV.

The windings 49 may be either in series or shunt with the windings 35, as desired. And whether the dashpot plunger be wound, or merely a magnetic body, I prefer to use the magnetic circuits indicated in Fig. XI., or the exact converse of the same, under which conditions the mutual relations would be the same.

Fig. V. diagrammatically portrays one type of system in which my invention is incorporated. In the said figure the resistance 4 is shown as regulating the voltage upon a translation circuit carrying lamps or other translating devices, indicated at 53, upon which it is desired to have impressed constant voltage, notwithstanding the fluctuations in voltage which may take place across the storage battery 52 throughout its discharge, or while being charged by the gen-

erator 50, at times connected with the battery and translating devices by means of switch 55.

If in any of the forms of my invention above described the operating windings 35 be connected across the translation circuit, as the coil 56 is shown connected, and the spring or springs in any of the types above mentioned properly adjusted, as the spring 57 in Fig. V. may be presumed to be, the pile 4 may be under considerable pressure, due to the said spring tending to straighten the toggle-joint 38, 39, 40, unless the voltage across the translation circuit tends to rise above a desired maximum value, under which conditions the knuckle 39 will be moved against the action of spring 57, to cause the pressure upon the pile 4 to be lessened, and the resistance thereof increased to lower the voltage across the translating devices 53, which voltage may be held substantially constant in this manner.

I do not wish in any way to limit myself to any of the details of construction nor exact modes of operation set forth in the above specification for the purpose of describing an embodiment of my invention.

For, it will be obvious, that wide departure from the exact constructions and details may be made without departing from the spirit and scope of my invention, which is as set forth in the following claims:

1. Means for regulating an electric circuit comprehending in combination therewith, a regulating element the effect of which depends upon pressure applied thereto, means for applying said pressure at varying rates comprehending a toggle-joint, and electro-magnetic means coöperating therewith for moving the knuckle of said joint comprehending means for maintaining a dense and confined magnetic field affected by the operation of the regulating means and movable means operating in said field and responding to fluctuations in electrical conditions of said circuit.

2. Means for regulating an electric circuit comprehending in combination therewith, a regulating element the effect of which depends upon pressure applied thereto, means for variably applying said pressure comprehending a toggle-joint and electro-magnetic means for moving the knuckle of said joint coöperating therewith to control said circuit comprehending means for maintaining a dense and confined magnetic field condition affected by variations in said circuit and movable electro-magnetic means operating in said field.

3. Means for regulating an electric circuit comprehending a regulating element the effect of which depends upon pressure applied thereupon, means for applying variable pressure thereon comprehending a toggle-joint, electro-magnetic means for moving

the knuckle of said joint coöperating therewith to regulate said circuit comprehending means for setting up a dense and confined magnetic field, movable means affected by said field, and means affected by said circuit for magnetizing said last mentioned means.

4. Means for regulating an electric circuit comprehending in combination therewith, a regulating element the effect of which depends upon pressure applied thereupon, means for applying pressure comprehending a toggle-joint, means tending to move said joint to increase said pressure, electro-magnetic means for moving the knuckle of said joint to decrease said pressure comprehending means for setting up a dense and confined magnetic field affected by conditions of said circuit and movable means affected by said field, and means for energizing said last mentioned means.

5. Means for regulating an electric circuit comprehending in combination therewith, a plurality of contacting members in operative relation to said circuit, combined with means for applying pressure at increasing rate upon said contacting members comprehending a toggle-joint, and adjustable means tending to cause the members of said joint to assume the direction of a straight line, combined with electro-magnetic means in operative relation to the circuit to be governed for controlling the angle between the members of said joint, said electro-magnetic means comprehending means for maintaining a strong magnetic field across a confined air gap responsive to conditions in said circuit and a magnetic member movable within said gap in response to fluctuations in said conditions.

40 6. Means for regulating an electric circuit comprehending in combination therewith, a plurality of contacting members in operative relation to said circuit, combined with means for applying the pressure upon said contacting members at increasing rate comprehending a toggle-joint, and adjustable means tending to cause the members of said joint to assume the direction of a straight line, and electro-magnetic means in operative relation to the circuit to be governed for controlling the angle between the members of said joint, said electro-magnetic means comprehending means for maintaining a strong magnetic field across a confined air gap responsive to said circuit and an electro-magnetic member movable within said gap affecting said angle.

7. Means for regulating an electric circuit comprehending in combination therewith, a plurality of contacting members in operative relation to said circuit, combined with means for applying the pressure upon said contacting members comprehending a toggle-joint, means tending to cause the members of said joint, to assume the direction of a straight line, and electro-magnetic means in operative

relation to the circuit to be governed for controlling the angle between the members of said joint, said electro-magnetic means comprehending means for maintaining a strong magnetic field across a confined air gap, a magnetic member movable within said gap, and means for energizing said movable member responsive to fluctuations in said circuit.

8. In an electric system, means for regulating a circuit thereof comprehending pressure-responsive regulating means affecting said circuit, operating means controlling the pressure thereupon including a plurality of movably united compression members of substantially equal length, pressure-exerting means tending to forcibly dispose said members so as to increase the distance between their opposite ends against the counter-pressure of the pressure-responsive means and normally when unaffected by a modifying force causing said members to assume the position of approximate alinement with each other, and magnetic means opposing the aforesaid pressure-exerting means and varying the angle between said compression members in response to fluctuations in magnetic strength which is responsive to fluctuations in a circuit of said system and, by virtue of the above-mentioned angular relation of said compression members, affecting the pressure upon the regulating means to compensate for slight fluctuations in the circuit to be regulated.

9. Regulating means for controlling a circuit of widely varying load throughout a wide range of regulating effect, comprising a compression rheostat requiring great pressure at one end of its range of operation and very small pressure at the other, of means for applying and controlling said pressure comprising a toggle-joint composed of substantially equal limbs, yielding means normally holding said limbs in close approximation to a straight line to greatly multiply the pressure upon the rheostat by this relationship, and electromagnetic means affected by electrical fluctuations in the circuit to be regulated for moving the knuckle of said joint to thus gradually and with increasing degree of motion draw the opposite ends of said limbs together to lessen the pressure upon said rheostat, said magnetic means being thus rendered capable of being operated by small fluctuations taking place in the circuit to be regulated.

10. Means for regulating an electric circuit comprehending a plurality of contacting members in operative relation to said circuit, combined with means for varying the pressure upon said contacting members comprehending a toggle-joint with its knuckle substantially midway between its opposite ends, means tending to cause the knuckle of said joint to be forced into aline-

6
ment with the aforesaid opposite ends to increase the pressure upon said members at an increasing rate and normally holding said knuckle approximately in line with the 5 opposite ends of said joint and electromagnetic means in operative relation to the circuit to be governed for moving the knuckle of said joint and varying the angle between

said members upon slight fluctuations in voltage across the circuit to be governed whereby the voltage upon said circuit is held substantially constant.

Certificate of Correction.

It is hereby certified that in Letters Patent No. 1,394,972, granted October 25, 1921, upon the application of John L. Creveling, of Auburn, New York, for an improvement in "Electric Regulation," errors appear in the printed specification requiring correction as follows: Page 4, line 121, claim 2, strike out the word "condition," and line 122, after the word "circuit" insert the word *conditions*; same page, line 126, claim 3, after the word "comprehending" insert the words *in combination therewith*; same claim, page 5, line 5, after the word "circuit" insert the word *conditions*; and that the said Letters Patent should be read with these corrections therein that the same may conform to the record of the case in the Patent Office.

Signed and sealed this 21st day of February, A. D., 1922.

[SEAL.]

WM. A. KINNAN,

Acting Commissioner of Patents.
